SEWING MACHINE

Peter P. Greicius, Chicago, Ill.

Application May 26, 1937, Serial No. 144,956

6 Claims. (Cl. 112—214)

My invention relates to sewing machines and includes among its objects and advantages the provision of an improved feed and presser mechanism.

5 In the accompanying drawing:

Fig. 1 is a fragmentary view of a sewing machine showing my invention applied thereto;

Fig. 2 is a view of the structure shown in Fig. 1 rotated 90°;

10 Fig. 3 is a sectional view along the line 3—3 of Fig. 2;

Fig. 4 is a sectional view along the line 4—4 of Fig. 3;

15 Fig. 5 is a sectional view along the line 5—5 of Fig. 4;

Fig. 6 is a sectional view along the line 6—6 of Fig. 5; and

20 Fig. 7 is a perspective view of a fragment of a curtain showing the manner in which the stitching may be made.

In the embodiment selected to illustrate my invention I make use of a conventional sewing machine of the zigzag lock stitching type, such as is manufactured by the Singer Manufacturing Company. In Figs. 1 and 2, I illustrate the head of the machine at 10. The head 10 carries a needle bar 12 to which the needle 14 is fastened. The bed 16 of the machine carries a throat plate 18 having an elongated opening 20 for accommodating the needle 14. Head 10 is also provided with a presser shaft 22 which carries a conventional presser foot. In the instant case I illustrate the shaft 22 as being slotted at 24 for the reception of the shank 26 of the presser foot, 35 which shank is cut off at 28 and the presser foot removed.

A rock shaft 30 has one end rotatably supported in a bracket 32 attached to the head 10. In a conventional machine the rock shaft 30 accommodates a reciprocating spring presser blade which is removed for the purpose of accommodating my invention. I also remove the feed dogs such as are used in connection with the throat plate 18. The structure so far described is standard equipment and need not be described in further detail.

My invention resides in the feed and presser unit 34. This unit comprises spaced flanges 36 between which a feed roll 38 is positioned. I prefer to make the feed roll of resilient rubber, and the roll is mounted on a shaft 40 rotatably mounted in openings 42 in the flanges 36 (see Fig. 6). Shaft 40 is provided with a transverse opening for the reception of a key pin 44 lying 55 within a groove 46 in one end of the feed roll 38.

The length of the feed roll 38 is substantially equal to the spacing between the flanges 36.

Feed roll 38 is illustrated as being arranged in pressure relation with a small roll 48 rotatably mounted on a shaft 50 having its ends supported on depending ears 52 carried by the throat plate 18, which plate is slotted at 54 to accommodate the roll 48 so as to bring the latter and the feed roll 38 into proper pressure relation.

Feed roll 38 is actuated so as to impart intermittent feeding movements to the work being sewed. To this end the shaft 40 is provided with a reduced reach 56 upon which a ratchet wheel 58 is fixedly connected. To the rock shaft 30 I fixedly connect an arm 60 by a screw 62'. The upper end of the arm 60 is forked to provide spaced flanges 62 between which one end of the pawl 64 is positioned and pivotally mounted on the shaft 66 carried by the flanges 62. In Fig. 3, I illustrate the lower end of the pawl 64 as being provided with an end 68 shaped to have operating relation with the ratchet wheel 58. Shaft 30 rocks sufficiently far to oscillate the arm 60 within the limits of the full and dotted line illustrations of Fig. 3.

On the flange 36 adjacent the ratchet wheel 58 I mount a small pawl 70. This pawl is pivotally mounted on a screw 72 anchored in the flange, and a suitable spring 74 is provided for urging the pawl against the wheel. In shifting the arm 60 from the full to the dotted line position of Fig. 3, the wheel 58 will be rotated sufficiently far to permit the pawl 70 to drop behind the tooth 76, as illustrated in connection with tooth 78. Such engagement prevents counter-rotation of the feed roll 38. At the same time the end 68 which lies behind the tooth 80 will fall behind tooth 78. To hold the pawl 64 in operating relation with the wheel 58 I connect one end of a tension spring 82 with the pawl and its other end with the bracket 60. It will thus be seen that work pressed between the feed roll 38 and the bed roll 48 will move intermittently in the direction of the arrow 84 across the bed 16.

Flanges 36 are formed integrally with a wall 86 which terminates in a reach 88 having flanges 90 bored at 92 to loosely receive the rock shaft 30. This shaft serves as a pivotal support only for the unit 34. Feeding pressure on the work being sewed is applied to the unit 34 through the medium of the presser shaft 22 (see Fig. 5) which has the portion 26 of the presser foot bearing against the wall 86, as at 28.

On the forward edges of the flanges 36 I mount a presser foot 94 which includes two reaches 96 55

each slotted at 98 to accommodate the screw 100 having threaded relation with its respective flange. The presser foot may be adjusted toward and away from the throat plate 18 and secured in all adjusted positions by merely tightening the screw 100. Reaches 96 are bent to provide angular reaches 102 (see Fig. 5) and horizontal reaches 104 which are connected integrally with the plate 106 bent upwardly at 108 to facilitate movement of the work underneath the presser foot. A bar 110 is welded or otherwise secured to the angular reaches 102, which bar is arranged in spaced relation with the edge 112 of the plate 106 (see Fig. 6) to provide an elongated opening 114 for accommodating the needle 14. Opening 114 registers with the elongated opening 20.

In operation, the intermittent rotation of the feed roll 38 carries the work being sewed across the table 16 in the direction of the arrow 84. In a sewing machine of the zigzag type, the needle 14 shifts laterally back and forth, as indicated in full and dotted lines in Fig. 2, but since the work being sewed is moving in a path at right angles to the direction in which the needle shifts, the stitch will be of zigzag formation, as indicated at 116 in Fig. 7. In sewing work, it is desirable that the thread be properly tied or fastened at the beginning and end of a line of stitch. Fig. 7 illustrates the manner in which the zigzag stitching is completed at the finish end of the line of stitch, which is identical with the starting end. As the zigzag stitching 116 approaches the end 118 of the curtain hem 120, the zigzag stitching terminates at 122, and a number of parallel stitches 124 completes the sewing.

The pawl 64 imparts a stitch movement to the curtain in each of its movements from the full to dotted lines in Fig. 3. So long as the pawl 64 is arranged in operating relation with the ratchet wheel 58, the work will continue moving in the direction of the arrow 84. As the zigzag stitching approaches the end 118 of the curtain of Fig. 7, the pawl 64 is manually raised out of operating relation with the ratchet wheel 58. Such raising of the pawl prevents further feeding of the work so that continued operation of the machine will form the stitching 124 (see Fig. 7) because of the shifting action of the needle 14.

In Fig. 6, I illustrate the plate 106 as being provided with a sight opening 126 which indicates the moment at which the pawl 64 should be raised. As the work moves across the bed 16 and the stitching approaches the end 118, the pawl 64 is lifted as soon as the end 118 is visible through the opening 126. With the end 118 so positioned, the stitching 124 will be properly positioned with respect to the end.

The feed roll 38 in being constructed of rubber of a slightly resilient nature embodies an effective action on the work being sewed. While I have shown the feed roll 38 in association with the bed roll 48, good results have been attained without the bed roll. In either event the conventional feed dogs are eliminated, and the feed roll 38 is of such shape and material as to protect the work being sewed. This is an important feature when sewing material of many types, particularly curtain material. Conventional feed dogs embody sharp projections, and the action is such as to leave marks on and frequently cause damage to the material being sewed. My roller leaves no marks on and causes no damage to the work. At the same time, the feed roll embodies a presser function, but rotation of the feed roll may be stopped at any time by merely lifting the pawl 64.

To facilitate lifting of the pawl I connect a pin 128 therewith for grasping purposes. Upward pressure on the pin 128 will pivot the pawl 64 away from the ratchet wheel 58 against the tension of the spring 82. The spring 82 pulls the pawl into operating relation with the ratchet wheel 58 as soon as the pawl is released.

In Figs. 4, 5 and 6 I illustrate the wall 86 as being provided with a thread cutting knife 130 which has a sharpened and hooked end 132 located slightly in the rear of the feed roll 38. As the end 118 of the work is reached, the thread 134 is pulled laterally of the blade 130 and severed. The blade is sharpened along the edge 136 as well as along its hooked part.

In starting the stitching 116, the end of the material being sewed is properly positioned underneath the presser foot 84; the pawl 64 is raised; and the machine is operated to stitch the material, as indicated at 124. After the proper amount of stitching has been made, the pawl is dropped, after which movement of the material brings about the diagonal stitching 116. Flanges 36 are provided with oil holes 140 to permit oiling of the shaft 40.

Without further elaboration, the foregoing will so fully explain my invention that others may, by applying current knowledge, readily adapt the same for use under various conditions of service.

I claim:

1. In a sewing machine, the combination with a rock shaft and stitch forming mechanism, of a feed roll for intermittently moving work in timed relation with the stitch forming mechanism, means connected with the rock shaft and the feed roll for supporting the latter, and an operating connection between the rock shaft and the feed roll for imparting intermittent motion to the latter.

2. In a sewing machine, the combination with a rock shaft, a presser shaft and stitch forming mechanism, of a carrier pivotally mounted on the rock shaft and having a feed roll for intermittently moving work in timed relation with the stitch forming mechanism, said carrier being arranged in pressure relation with said presser shaft, said feed roll including a ratchet wheel, an arm carried by said rock shaft, and a pawl pivotally connected with said arm and operatively connected with the ratchet wheel for intermittently rotating the feed roll.

3. In a sewing machine of the zigzag lock stitching type, the combination with a rock shaft and stitch forming mechanism, of a carrier movably mounted on the rock shaft and having a feed roll for intermittently moving work in timed relation with the stitch forming mechanism, means connected with the rock shaft and engaged with the feed roll for actuating the latter, to impart intermittent motion thereto, means for holding the feed roll in pressure relation with the work being stitched, and a presser foot carried by said carrier in advance of the feed roll.

4. In a sewing machine of the zigzag lock stitching type, the combination with a rock shaft and stitch forming mechanism, of a carrier movably mounted on the rock shaft and having a feed roll for intermittently moving work in timed relation with the stitch forming mechanism, means connected with the rock shaft and engaged with the feed roll for actuating the latter, to impart intermittent motion thereto, means for holding the feed roll in pressure relation with the work being stitched, and a presser foot carried by said carrier in advance of the feed roll.

said presser foot being adjustably mounted on said carrier.

5. In a sewing machine, the combination with a rock shaft and stitch forming mechanism, of a feed roll for intermittently moving work in timed relation with the stitch forming mechanism, means connected with the rock shaft and the feed roll for supporting the latter, an operating connection between the rock shaft and the feed roll for imparting intermittent motion to the latter, and a work supporting bed roll arranged in operative relation with the feed roll.

6. In a sewing machine, the combination with a rock shaft and stitch forming mechanism, of a feed roll for intermittently moving work in timed relation with the stitch forming mechanism, means connected with the rock shaft and the feed roll for supporting the latter, and an operating connection between the rock shaft and the feed roll for imparting intermittent motion to the latter, said feed roll comprising resilient material. 5

10 PETER P. GREICIUS.
